SHOE SEWING MACHINE

Frank A. Larson, Saugus, Mass.

Application January 18, 1936, Serial No. 59,723

20 Claims. (Cl. 112—38)

This invention relates to sewing machines, and more particularly to lock stitch, curved hook needle machines such as are commonly employed for securing the outsoles to boots and shoes. In machines of this kind, owing to the fact that the several operative instrumentalities require to have variable quick and slow movements and dwells between movements, it has heretofore been deemed necessary to employ numbers of cams or equivalent devices, and special gearing arrangements, all of which have produced a large complement of friction and consumption of power and hence machines so constructed have required considerable power to operate them so that they are impracticable or difficult for manual operation as well as involving rapid wear of the parts and causing vibrations in the machine.

The prime object of the present invention is to produce a machine of the kind stated wherein substantially all of the requisite movements are imparted to the usual or necessary instrumentalities of such a machine by special and novel arrangements of links and levers from a common drive shaft. In accordance with my invention, such system of links and levers are arranged and adapted to produce all of the varied fast and slow change movements and dwells of the operative parts of the machine. By thus substantially eliminating friction producing transmission such as cams and special gearing, I make the machine very much easier to operate and so that it can be readily operated by manual power if desired. The invention also comprehends certain special improvements in the operative instrumentalities as will be later described.

The foregoing and other objects and advantages of the invention will be better understood from the following detailed description taken in connection with the accompanying drawings, and the distinctive features of novelty will be thereafter pointed out in the appended claims.

Referring to the drawings:

Figure 1 is a side elevation of a machine embodying my invention with parts broken away in section,

Figure 2 is a side elevation from the opposite side of the machine to Figure 1, showing essential portions of the improved link and lever arrangements,

Figure 3 is a partial plan view showing particularly the linkage arrangement of Figure 2,

Figure 4 is a partial end view looking in the direction of the arrows 4—4 of Figure 2,

Figure 5 is a detail elevation showing the nee-

dle, needle guide, awl, and loop-spreader motion.

Figure 6 is a plan view of the mechanism of Figure 5,

Figure 7 is a sectional detail on line 7—7 of Figure 5,

Figure 8 is a detail elevation of the needle, needle guide and awl motion, showing the origin of the motion from the main shaft,

Figure 9 is a detail elevation of the loop-spreader motion,

Figure 10 is a detail elevation of the shuttle-motion showing its origin from the main shaft of the machine,

Figure 11 is a detail elevation of the take-up lever motion showing its origin from the main shaft,

Figure 12 is a detail elevation showing the looper motion with its origin from the main shaft,

Figure 13 is a detail elevation showing the loop-control arm, or loop-hook and the operating means thereof,

Figure 14 is a detail of the feeding mechanism showing its origin from the main shaft, and

Figure 15 is a detail view looking in the direction of the arrows from the line 15—15 of Figure 14.

All of the operative means to be described are derived from a main shaft 1 journaled in the base portion of a suitable machine framework 1a. Such operative movements will now be severally described:

I.—Looper and loop-hook motion

Referring particularly to Figures 12 and 13, the looper and loop-hook motion is derived from the main shaft 1 through a crank arm 2 on the main shaft 1 which oscillates a horizontal shaft 3 through a connecting link 4 and upright arm 5 which is pinned to shaft 3. Oscillating with shaft 3 is a small upright arm 6. Pivoted to this arm is a link 7 which operates through three links 8, 9 and 10 to effect oscillating motion in a gear segment 11, and to turn a gear 12 which is fixed to the shaft of looper 13. The arrangement of the links 7, 8, 9 and 10 is such that as the main shaft turns from its position, shown in Figure 12, towards its opposite extreme position for this motion, shown in dot and dash lines in the same figure, during the first part of such movement the looper remains without motion or an extremely small amount of motion, this being during a period of time in which the main shaft has rotated to a position shown in Figure 55

8 when the needle 14 is down through the work. Then while the main shaft 1 moves from its position shown in Figure 8 to the extreme position of Figure 12, a direct downward pull on the link 10 through links 7, 8 and 9 affords a quick rotary motion to the looper 13 which casts the thread about the needle barb, according to usual practice. It will be understood that the described movement results because starting from 10 the full line position shown in Figure 12, the downward movement of the link 7 to straighten the toggle links 8 and 9 operates through the link 9 upon the link 10 approximately at right angles thereto giving it very little movement, 15 it being noted that the arm 5 is then in a position to impart least movement to the link 7. After the parts are moved downward past the straightened position of the links 8 and 9, the link 9 is then pulling downward relatively close 20 to the turning axis of the link 10 causing the link 10 and hence the looper to receive a relatively much increased movement in the last part of the downward pull of the links 7 and 9. It is to be further noted that the degree of this differential movement is further accentuated by 25 the relative arrangement of the arms 5 and 6 upon the shaft 3.

From the same connections, movement is taken to operate the loop-hook 15 as seen in Figure 13. 30 This loop-hook 15 is fulcrumed on the main frame in proper relation to the looper 13, as shown in Figure 2, and is operated by a bell crank arm 16 through a link 17 which is fulcrumed to the stud 18 which is a connecting stud for links 35 7, 8 and 9. The motion given to this loop-hook is a uniform motion. While the system of links and levers for actuating the active instrumentalities of my invention is of value and importance for operating elements such as the loop-hook 15 40 which has a relatively uniform motion, such system is of particular value for operating those instrumentalities which require to have a quick operative movement with a slow movement or dwell between operating movements as above 45 described for the looper. For the other operating elements to be now described, I employ linkage including toggle link systems generally similar to the link system 7, 8 and 9 and which obtain the required movements without the use of friction creating gears and cams. 50

II.—Needle motion

The needle motion as best seen in Figure 8, is taken directly from the main shaft 1 by means 55 of an extension of the crank arm 2 carrying stud 19 to which is pivoted needle lever 20, which operates the oscillating needle holder 21, an awl carrier 21a, and the needle guide 22. The link 23 connecting the needle lever 20 affords the 60 needle guide its proper timing. To adjust the needle guide position in relation to the needle barb, an eccentric or like means 22a may be applied to the connecting stud at one end of the link 23. The needle motion which is given to the 65 needle holder 21 is transmitted to the awl carrier by a dowel pin 21b fastened to the awl carrier 21a and working loosely in a hole in the needle holder or clamp 21. This allows the awl carrier 70 to move laterally for feeding the work while being turned by the dowel pin 21b. As later more fully explained, provision is made for changing the rate of such work feeding movement of the awl carrier while the machine is in operation and 75 the needle holder in movement.

III.—Loop-spreader motion

As best seen in Figure 9, the loop-spreader motion is taken from the needle clamp arm through a link 24 pivoted thereto at one end 5 and having its other end pivoted to a pair of toggle links 25, 26. When the main shaft rotates to a position shown in dot and dash lines in Figure 8, the needle clamp arm is brought to a position shown in dot and dash lines in Figures 10 8 and 9 which in turn draws the toggle links 25, 26 downward, rotating shaft 28 by means of the universal link 27 secured to said shaft. Being fastened to shaft 28 the loop-spreader 29 receives an upward swing shown in dot and dash lines in Figure 9 at the same time that the shaft 28 receives its rotating motion. It will be noted 15 that the arrangement of links 24, 25 and 26 is similar to that of links 7, 8, 9 of the looper motion, and affords to the loop-spreader a quick 20 motion after a dwell, similar to that given to the looper.

IV.—Shuttle motion

As best seen in Figure 10, pivoted to the stud 19 which, as stated is carried by an extension of 25 crank arm 2, is a link 30 attaching to a crank arm 31 pinned to a shaft 32 journaled in the machine frame. Owing to the link connection from one crank to the other, the motion given to shaft 32 is an uneven fast and slow motion alternating during each revolution. From this motion is taken the shuttle motion shown in Figure 10 and to produce such motion with the proper timing a crank arm 33 is pinned to the shaft 32. 30 On this crank arm 33 a link 34 extending angularly thereto is pinned to stud 35 carried by the crank arm 33, and an oscillating motion is transmitted to a shaft 36 fulcrumed in the main frame by a connecting link 37 from the link 34 to the 35 crank arm 38 fixed on a shaft 36. The necessary oscillating shuttle motion is taken from the crank arm 38 by a connecting link 39 through a gear segment and gear 40, 41 and a bell crank 40 arm 42 and thence to the shuttle housing 43. 45

V.—Thread tension control

As best seen in Figure 2, a positive thread tension control arm 44 has an arm 45 extending obtusely rearward therefrom, these two arms 50 being in one and constituting a bell crank lever fulcrumed to the machine frame. From the arm 45 a link 46 extends to a short crank arm 47 pinned to the oscillating shaft 36 which constitutes a part of the shuttle motion as described. 55 The arm 44 carries at its extremity a small roller 48 over which the thread T passes, the motion which this roller receives being such, that while the usual thread tension spring may be employed, the thread is kept taut at all times without being placed under a breaking strain, without the aid of the ordinary tension spring. In regard to this motion it will be noted that at the time the toggle arrangement 7—8—9 operates on link 16, moving loop-hook 15 rearward carrying 60 with it the thread T, the arm 44 moves downward giving to the loop-hook the necessary amount of thread, and continues to move downward as the looper 13 casts the thread about the needle barb thereby giving to the looper its proper length of 70 thread. At this point the loop spreader 29 takes the thread to cast it about the shuttle while the take-up arm 74 (to be presently described) gives the necessary amount of thread, and while the take-up returns to its downward position tak- 75

ing-up the surplus thread in making the stitch, the positive-thread tension control arm 44 also returns to its normal upward position. The action of the two levers 44 and 74 working in opposite directions at the crucial moment when the stitch is being made insures a good tight stitch. Cooperating with this mechanism an automatic thread measuring device (to be presently described) aids in obtaining a tight and even stitch.

10

VI.—Feeding motion

As best seen in Figure 14, the feeding motion is also controlled by the shaft 36. Pinned to this shaft is a link 49. A connecting link 50 from link 49 to arm 51 which is pinned to a stud 52 fulcrumed in the machine frame, gives an oscillating motion to the cam 53 which is also pinned to the stud 52. A forked lever 54 fulcrumed in an adjustable housing 55 receives a rocking motion which is transmitted as an oscillating motion to shaft 56 through universal connecting links 57, 58. Pinned to the shaft 56 is a forked link 59 which straddles a pin 60 projecting from a hollow shaft 61 giving it a reciprocating motion which is thus given to an adjustable pin 62 held in hollow shaft 61 by suitable clamping means as seen at 63. Fastened to this pin 62, is a yoke 64 which straddles the awl carrier 21a giving to it the described reciprocating motion for feeding the work, it being understood that the present machine is of that type wherein the work is fed by a lateral movement of the awl while engaged through the work. To obtain an adjustment for aligning the awl with the needle, the yoke 64 is secured to the pin 62 by a shouldered screw 65 allowing the pin 62 to be turned. This pin carries a threaded portion that screws into the hollow shaft 61, which has an internally threaded portion for this purpose, and by turning the pin 62 by its knurled head 66, the awl can be moved laterally for the necessary adjustment. The feeding cam 53 is so located on stud 52 that the proper dwell and feeding motion is obtained with the assistance of the linkage 49, 50 and 51. The arrangement of these links is also similar to that of the links 7, 8, 9 of the looper motion, and affords a quick feeding motion. The amount of feed is governed by changing the fulcrum point of the forked lever 54 by moving the housing 55 which carries this fulcrumed point along the horizontal shaft 67 carried in the machine frame, by use of the handle 68, as seen in Figure 1, which is fulcrumed to the frame at 69, and connected to housing 55 by link 70. It is thus possible to change the amount of feed, i. e., the spacing of the stitches while the machine is in operation by operating the handle 68.

60

VII.—Take-up motion

As best seen in Figure 11, the take-up motion is derived from the stud 35 on the crank arm 33 pinned to the shaft 32 which is supplied with an uneven and alternating fast and slow motion as previously described. Pivoted at one end to this stud 35 a link 71 connects to a bell crank 72 fulcrumed on the shaft 36. A connecting link 73 connects the arm 72a of this bell crank to the take-up lever 74 which is fulcrumed to the machine frame at 75. The lever 74 bears at its extremity a small roller 74a around which the thread T passes from the tension roller 48 to the shuttle and needle mechanism.

VIII.—Presser foot mechanism

As best seen at Figure 2, the presser foot mechanism derives its movement from the stud 76 which is the connecting stud for the take-up bell crank 72 and its connecting link 71. The motion of this bell crank is transferred to another bell crank 77 fulcrumed to the machine frame at 78, by a connecting link 79. Attached to the bell crank 77 is a link 80 carrying a cam roll 81, which cam roll is also connected to, and under the control of, a link 106 to be later further described. This cam roll operates in a cam slot in a lever 82 which is fulcrumed to the machine frame at 83. Attached to this lever 82 by stud 84 is a block 85 adapted to slide in a frame or housing 86. This frame 86 is attached to a presser foot lever 87 fulcrumed on the machine frame at 88. Two locking pins 89, 90 held in wedge shaped grooves in the slide block 85 by flat springs 91, 92, lock the slide block 85 in its frame 86 causing the frame and block to move as one unit. After the cam lever 82 has been forced downward by the action of the cam roll 81 in the cam slot, thus raising the presser foot 93, the flat faces of the cam lever 82 shown at 94, 95 come to such an angle as to act against the rollers 96, 97 borne by the ends of locking pins 89, 90, causing the locking pins to release the slide block 85, this constituting a self-disconnecting device which then allows the spring 98 to act on the presser foot lever 87 through lever 99, fulcrumed at 99a and engaging the presser foot lever at 99b; thus moving the presser foot down to operative position. The presser foot can also be operated manually by handles 100, 101. Handle 101 effects the release of locking pins 89, 90 through the toggle links 102, 103 connected thereto by link 104, which links are connected at one end to the machine frame and at their other end to the rocking lever 105 which through a link 106 is connected to the cam roller 81. The handle 100 which is fastened to the presser foot lever may be used to lift the presser foot.

IX.—Automatic thread measuring device

As best seen in Figures 1 and 2, a mechanism is employed to automatically measure and take from the spool the amount of thread to be used in making each stitch. As the amount of thread, necessary, varies with the thickness of the material which is being stitched, the device is controlled by the presser foot 93 which bears on the work, continually acting as a caliper. Pinned to the extremity of shaft 99a is an arm 107 with a projecting pin 108. Fulcrumed in the machine frame at 109, an arm 110 is held against the pin 108 by spring 111 fastened to the frame. In the underside of arm 110 a screw 112, which may be felt capped, is in position to be contacted by the bell crank arm 72a of bell crank 72 in its upward travel. A spring 113 is fastened to arm 110. The thread comes from the spool and is temporarily gripped between the pin 108 and underside of arm 110; it then passes through a hole in arm 107 for controlling purposes and thence up and under spring 113 where it is permanently, gently gripped by spring 113 bearing down on it. Thence it continues to the wax pot, up over the positive-thread-tension control arm 70 roller 48, thence to the take-up arm roller 74a, and on to the looper 13. As the bell crank arm 72a travels in its upward motion, it strikes against the screw 112, which may be adjusted in or out, raising arm 110 from its resting posi-

70

75

tion on pin 108. As thread is being gripped at this point, it will be noted that as the arm 110 is raised, the thread is immediately released, and being permanently gripped by spring 113 attached to arm 110, an amount of thread is drawn from the spool which is governed only by the amount of lift that is transmitted to arm 110. As the bell crank arm 72a moves to its downward position returning arm 110 to its gripping position on pin 108, the amount of thread drawn from the spool rests in loop form on the forward side of pin 108, ready to be used for the coming stitch. As the presser foot is raised or lowered, it will be noted that shaft 99a is oscillated which in turn raises or lowers the contacting pin 108 thereby governing or determining the amount of lift which is to be given to arm 110 and consequently controlling the amount of thread necessary for the stitch in the thickness of work on which the presser foot rests. It will be noted that at the time the arm 44 and arm 74 are working against each other to draw the stitch tight, that the action of the thread on arm 110 is such that it is pulling it downward on pin 108 thereby tending to grip the thread harder, the tighter the stitch is being drawn.

Certain other features of, or accessories to, a complete lock stitch sewing machine such as a heated wax pot for coating the thread, are not herein shown or described since they form no part of the present invention and have no novel cooperative relation with the features shown and claimed herein.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having now described my invention, what I claim as new and desire to secure by Letters 45 Patent is:

1. A lock stitch sewing machine comprising awl and needle mechanism, shuttle mechanism, work feeding mechanism, a prime drive shaft with connections to all of said mechanisms to operate the same, and a looper equipped with rotating means, said rotating means having a direct link and lever connection to the prime drive shaft embodying a plurality of cooperative toggle devices, one working through another and arranged to impart very quick operative movements to the looper rotating means with relatively long dwells between such movements.

2. A lock stitch sewing machine comprising a prime drive shaft having connections to operate all the operative instrumentalities of the machine, embracing a looper equipped with rotating means, said rotating means directly connected from the prime drive shaft by a crank on such shaft, a link from such crank, a bell crank connected to such link, a second link and a toggle device connected to the second link and to the looper rotating means arranged to impart to the looper quick operative movements with dwells between such movements.

3. A lock stitch sewing machine as described in claim 1 having a loop hook with a link connection to the toggle device to be operated in connection therewith.

4. A lock stitch sewing machine comprising a prime drive shaft, a work feed, and awl and

needle mechanism including an oscillating needle holder, connected to be operated from such drive shaft, such connection to the needle holder embodying a crank on the prime drive shaft, an arm extending from the needle holder and a direct link connection from said crank to said arm.

5. A lock stitch sewing machine as described in claim 4 having an oscillating needle guide with a link connection to an extension of the link which operates the needle holder arranged to impart a differential movement to the needle guide with respect to that of the needle holder.

6. A lock stitch sewing machine comprising awl and needle mechanism, work holding and work feeding mechanism, a single drive shaft connected to operate all of said parts and having a direct link and lever arm connection to the needle holder to oscillate the same, and a loop spreader having a linkage connection to the needle holder embodying a toggle link device arranged to impart quick operating movements to the loop spreader with intervening dwells.

7. A lock stitch sewing machine as described in claim 6 wherein the loop spreader is mounted to turn about an axis at an angle to the axis of the needle holder with a universal joint connection thereto from said toggle link device.

8. A lock stitch sewing machine comprising awl and needle mechanism, a work feed, an oscillating shuttle, a single drive shaft for all of said parts, and a link and lever system directly connected with both said shaft and said shuttle to turn the shuttle, arranged to impart quick operative movements to the shuttle with a dwell between such movements.

9. A lock stitch sewing machine as described in claim 8 wherein the connections from the prime drive shaft to the shuttle embrace a second shaft mounted in offset parallel relation to the prime drive shaft with a link and lever arm connection from one to the other arranged to impart an irregular alternating fast and slow movement to the second shaft, and with a link and lever connection from said second shaft to the shuttle adapted to accentuate such irregular motion to impart to the shuttle quick operative movements with a dwell therebetween.

10. A lock stitch sewing machine as described in claim 8 wherein the connections from the prime drive shaft to the shuttle embrace a second shaft mounted in parallel offset relation with respect to the prime drive shaft with a longer crank on the prime drive shaft connecting through a link with a shorter crank on the second shaft to impart irregular alternating fast and slow movements to the second shaft, and a link and lever arm connection from the second shaft to the shuttle arranged and adapted to increase the extent of such irregularity of movement to impart quick operative movements to the shuttle with dwells between such movements.

11. In a lock stitch sewing machine a single prime drive shaft connected to actuate all the operating instrumentalities of the machine, a shuttle, and a toggle link system of connections from said shaft to the shuttle arranged to operate the same with quick operating movements and a dwell between such movements.

12. In a lock stitch sewing machine having awl and needle, shuttle, and work feed mechanisms, a prime drive shaft for operating all said mechanisms, connections from said shaft to the shuttle including a toggle link system and a shaft for imparting quick operative movements to

the shuttle with a dwell between such movements, and a thread tension control device embracing a bell crank lever having a link and lever arm connection to said shaft 36 to be actuated thereby.

13. A lock stitch sewing machine comprising a prime drive shaft, awl and needle mechanism with the awl borne in an awl carrier, shuttle mechanism, and work feed mechanism, embracing a linkage system including a toggle device from the prime drive shaft to the awl carrier arranged to impart quick operative movements to the awl carrier with dwells between such movements.

14. A machine as described in claim 13 wherein the connections from the prime drive shaft to the awl carrier include also a lever mounted to turn on a fulcrum, said fulcrum having adjustment endwise of said lever for varying the rate of feed at will while the machine is in operation.

15. In a lock stitch sewing machine a prime drive shaft, a shuttle, a linkage system for turning the shuttle from said prime drive shaft constructed and arranged to impart quick operative movements with a dwell between such movements to the shuttle, said linkage system embracing an oscillating shaft 36, an awl carrier, and means for reciprocating said awl carrier from the shaft 36 embracing a toggle device adapted to impart quick operative movements to the awl carrier with dwells between such movements and embracing also a lever having a fulcrum adapted for adjustment while the machine is in operation to vary the rate of feed.

16. A lock stitch sewing machine comprising a prime drive shaft, awl and needle, shuttle, and work feed mechanisms connected thereto, such connection to the shuttle including a second shaft mounted in parallel offset relation to the prime drive shaft with means for turning it with an irregular fast and slow movement with respect to the prime drive shaft, and a thread take-up device comprising a bell crank lever having link and lever connections to operate it

from said second shaft, said link and lever connections arranged and constructed to partake of the fast and slow movements of said second shaft to impart quick operating movements to said take-up device with dwells between such movements.

17. In a lock stitch sewing machine a prime drive shaft, a thread take-up device, and a linkage system direct from said prime drive shaft to said take-up device embracing a plurality of cooperative toggle devices arranged in series with one working through another constructed and arranged to transmit and transform uniform movements of the prime drive shaft as quick operating movements of the take-up device with dwells between such movements.

18. A lock stitch sewing machine comprising a prime drive shaft, feed mechanism, awl and needle mechanism, and shuttle mechanism connected through toggle link connections to be actuated therefrom with quick operating movements and dwells between such movements, and a presser foot connected to partake of such quick operating movements with a self-disconnecting device interposed in such connection arranged to come into operation as the presser foot is lifted to a pre-determined degree, with spring means for thereafter depressing the presser foot to operative position.

19. An apparatus as set forth in claim 18 equipped with manual means for lifting the presser foot and with cooperative manual means for rendering said disconnecting device operative.

20. A lock stitch sewing machine comprising a prime drive shaft, shuttle mechanism, awl and needle mechanism, and feed mechanism with connections from the prime drive shaft to each of the said mechanisms, each of said connections embodying a linkage system including a toggle device adapted to impart quick operating movement to its operated element with a dwell between such movements.

FRANK A. LARSON.
